UNITED STATES PATENT OFFICE.

JOHN CUTHERBERT, OF CHICAGO, ILLINOIS.

SOCKET FOR ELECTRIC LAMPS.

1,214,900.

Specification of Letters Patent.

Patented Feb. 6, 1917.

Application filed December 2, 1915. Serial No. 64,634.

To all whom it may concern:

Be it known that I, JOHN CUTHERBERT, a citizen of the United States, residing at Chicago, in the county of Cook and State 5 of Illinois, have invented certain new and useful Improvements in Sockets for Electric Lamps, of which the following is a specification.

My invention relates to improvements in 10 sockets for electric lamps and other like translating devices.

One of the objects of my invention is to provide an improved socket that may quickly and easily be "wired" without removing the shell or any part thereof.

Another object of my invention is to provide improved means for taking up the slack of the wires, or cables within the shell and to securely hold said conductors in place 20 after they have been properly connected to the socket terminals and arranged so as to relieve said terminal connections of undue strain by any application of force or stress that may, at any time be applied tending to 25 separate said parts.

Another object of my invention is to decrease the cost of construction and to make the structure more stable and durable.

Other and further objects of my invention 30 will become readily apparent, to persons skilled in the art, from a consideration of the following description taken in conjunction with the drawings, wherein—

Figure 1 is an elevation of my improved 35 socket.

Fig. 2 is an enlarged central section taken on line 2—2 of Fig. 1.

Fig. 3 is a transverse section taken on line 3—3 of Fig. 2.

Fig. 4 is a transverse section taken on line 4—4 of Fig. 2.

Fig. 5 is a section taken on line 5—5 of Fig. 4.

Fig. 6 is a central section taken on line 45 6—6 of Fig. 2.

Fig. 7 is a transverse section taken on line 7—7 of Fig. 2.

Fig. 8 is a central section taken on line 8—8 of Fig. 9.

Fig. 9 is a central section taken on line 50 9—9 of Fig. 8.

Fig. 10 is a perspective view of a central terminal detail.

Fig. 11 is a section taken on line 11—11 55 of Fig. 2.

In all the views the same reference char-

acters are employed to indicate similar parts.

When installing the usual lamp socket it becomes necessary to disassemble the many 60 parts thereof before access to the wire connecting terminals can be had. The parts being constructed with this end in view are necessarily more expensive to produce and the wear, incident to frequent taking apart 65 and reassembling, renders such sockets relatively short-lived. After the wires have been clamped to the terminals of the ordinary socket said terminals and wires are hidden from view and are inaccessible until 70 the shell has again been removed. A wire may, therefore, become loose or disconnected without any visible evidence of this fact.

In my improved socket the terminals are 75 plainly visible through the open end of the socket shell and can be carefully inspected when the translating device, or lamp is removed therefrom and through this opening the terminal binding screws may readily be 80 tightened, to clamp the wires, by use of an ordinary screw driver.

Another advantage resulting from my new invention is the fact that the time required for the installation of sockets is very 85 much less than necessary for installing sockets requiring removal of the shell parts for this purpose.

There is much less strain on the terminal screws of my new socket, than of the old style socket, when stress is applied to the 90 socket tending to pull it from the wires, because, in my new sockets the wires are bent at right angles to the plane in which they are inserted, where they lie under the head of the terminal screws. Much of the strain 95 is therefore resisted by the shoulders where the wires are thus bent and not altogether by the screws themselves.

For the purpose of clear disclosure I have 100 illustrated a conventional form of socket without any intention whatever of confining my invention to the precise structure shown, wherein 20 is the socket; 21 is the major portion of the shell or casing and 22 the minor portion thereof. 23 is the insulating lining 105 of the larger portion of the shell and 24 is the insulating lining of the smaller portion, as usual in sockets of this general character. The shell portions of the socket are shown to telescope at their juncture and may be 110 secured together by any suitable means, The interior insulating porcelain base or

block 25, upon which the contacts are mounted, is centrally perforated, as at 26, for a screw 27, that holds the central contact 28 in place. Underlying the central contact 28 is preferably a fixed part of a spring contact 29 for direct connection with the central contact 30 of the lamp 31. The larger portion 32, of the contact plate 28 is centrally perforated as at 33 for a wire clamp-
 10 ing screw 34, and it is countersunk, as at 35, within which countersink the head of the screw may be received. The larger portion 32, of the contact plate 28 is contained between two porcelain ribs 36 and 37 joined by
 15 a porcelain bridge 38 upon which the contact 28 rests. These ribs are integral parts of the porcelain block 25. The ribs 36 and 37 serve as insulations for separating the contact terminal 32 and screw 34 from the other
 20 electrical conducting portions of the socket. The upper end of the contact plate 28 rests directly upon and is supported by the bridge 38 that joins the ribs 36 and 37. A screw threaded lamp-engaging shell 40 is
 25 secured in the smaller portion of the casing 21, by screws 41 that are let into perforations 42 in the block 25. They pass into screw threaded plates 43 and then into the inturned flange of the screw-threaded shell.
 30 Another terminal binding screw 44 is located on the diametrically opposite side of the center or axis of the socket, and is substantially in the same horizontal plane with the binding screw 34 and below the plane
 35 of the ribs 36 and 37 and the joining bridge 38 of the porcelain block 25. The binding screw 44 is threaded into a relatively stationary metal part 45, that is secured to the porcelain block 25 and connected to the
 40 threaded shell 40. The part 45 is also concentrically counterbored to receive the head of the screw 44 and within which to confine one of the circuit conductors or wires to be connected to the socket. The terminal
 45 plates 32 and 45 are each perforated concentrically with the counter-bores for the respective terminal screws and are also perforated, as at 46, the perforations in each case terminating in the counter-bored por-
 50 tion of the terminal plates and serve as means for conducting the electric circuit wires into said counter-bored portions. The porcelain block 25 is also perforated, to register with the respective perforations 46, as
 55 at 48, for introduction of the wires 49—49' therein. These perforations, are tapered, at their outer ends, as at 50, as shown clearly in Fig. 4, the taper being preferably to one side of the axis of perforations 46 and ex-
 60 tending toward the center of the socket. These tapered perforations serve as means for guiding the wires into the smaller parallel perforations when the wires are introduced through the angularly extending perfora-

tions provided in the bottom of the insulat- 65 ing bushing 51. The bushing 51 is provided with a bottom wall 52 having laterally diverging perforations 53 and 54 and a central depression 55. The duplex cable 56, 70 consists of the wires 49 and 49', from which wires the insulation is removed near the ends, prior to introducing them into the socket. When the wires 49—49' are threaded through the perforations 54 and 53, respectively, provided in the bushing 51 75 they are thereby directed into the tapered ends 50 of the perforations provided in the porcelain block 25. The insulated portions of the wires pass into the tapered apertures 50—50 thus protecting the wires, and the 80 uncovered portions of the wires pass through the relatively narrower parallel perforations which are continuations of the tapered perforations, and through the said narrower perforations they pass through 85 the perforations 46—46 made through the terminal plates 45. From the perforations 46 they pass into the cutaway portions 57 of the heads of the screws 34 and 44, of Fig. 3, just in front of the shoulders 58 90 of said screws. The screws are now turned clockwise by the use of an ordinary screw driver, introduced into the open or shell end of the socket, at which time the shoulders 58 of the screws 34 and 44 engage the 95 ends of the respective wires and bend them at substantial right angles and turn or bend them into substantially the shape of rings around the shanks of the screws. A continuation of the turning of the screws serves 100 to bind the wires between the plates 45 and the heads of the respective screws. The counter bored depressions in the plates prevent escape of the wires, and the screws by 105 this means hold them firmly in place.

The wire terminal screw illustrated in Figs. 8 and 9 forms the subject matter of Patent No. 1,166,114 for "wire clamping devices" issued to me December 28th, 1915, 110 whereas the terminal illustrated in Figs. 2, 3, 4 and 5 is described in detail and claimed in my application entitled "Electric terminals", serially numbered 64,635 filed on an even date herewith.

The bushing 51 is provided with two laterally projecting pins 58—58 that extend radially through the smaller hub portion 59 and which are slightly below the larger flange portion 60. The smaller hub portion 59 of the bushing 51 passes through an orifice or opening 61 in the minor shell portion 22. Immediately surrounding the orifice 61 is a flat inwardly extending flange 63 provided with a series of cut away tongues 64. The bushing 51 is placed in the opening 61 by 120 inserting the smaller or hub portion 59 therein and forcing the pins 58 inwardly beyond the tongues 64 and then turning the 125

bushing 51 thereby twisting the wires 49-49', to some extent within the socket, thus taking up the slack and putting the wires under some tension. The bushing 51 is prevented from rotating in the opposite direction by the tongues 64 which serve as stops for the pins 58, as clearly shown in Fig. 11. To remove the bushing 51, and thereby to reduce the tension and to slacken the wires within the socket the tongues 64 must be displaced. This may be done by means of a sharp instrument, such as the point of a knife, that may be inserted under the flange 60 of the bushing to depress the tongues 64 after which the bushing may be turned slightly and pulled outwardly which will permit the hub to pass out from the orifice in which it was primarily contained.

Twisting the wires within the socket, in 20 a manner described, will add considerable to the resistance that will be thus interposed to their removal against any stress that may be applied to pull the socket from the wires.

Having described my invention, what I claim is:

A socket comprising a shell open at one end to receive a translating device and open at the other end to receive circuit wires; an insulating block within said shell, having perforations to receive said wires; a rotatable bushing for insertion in the latter shell opening, having a plurality of perforations registerable with the perforations in said block, for a corresponding number of wires, and a yieldable ratchet means to permit the bushing to be rotated in one direction only, out of registration, to twist said wires within said shell. 25 30 35

In testimony whereof I hereunto set my hand in the presence of two subscribing witnesses. 40

JOHN CUTHBERT.
